WILLIAM C. REEVES, OF BOSTON, AND LOUIS L. SOLOMON, OF CHARLES-TOWN, MASSACHUSETTS.

Letters Patent No. 76,347, dated April 7, 1868.

IMPROVEMENT IN BUTTON-HOLES FOR PAPER ARTICLES OF WEARING-APPAREL.

The Schedule referred to in these Letters Patent and making part of the same.

TO ALL PERSONS TO WHOM THESE PRESENTS MAY COME:

Be it known that we, WILLIAM C. REEVES, of Boston, in the county of Suffolk, and LOUIS L. SOLOMON, of Charlestown, in the county of Middlesex, and State of Massachusetts, have invented a new and useful Improvement in Button-Holes, Wristbands, or other articles made of paper; and we do hereby declare the same to be fully described in the following specification, and represented in Figure 1 of the accompanying drawings.

The button-hole constituting our invention consists not only of a straight slit, A A, but of a recess or hole, B, arranged as exhibited in the figure. This recess, as exhibited in the figure, has parallel sides and a semi-circular end, or is composed of a rectangle, a, and a semicircle, b, the circumference of the latter corresponding with one side of the former. The slit a a need be only a straight cut, such as would be made by a sharp chisel or knife when cutting through paper.

This mode of forming a button-hole has a great advantage over one made as represented in Figure 2, in which the slit is represented as curved, in order to produce what is termed a fly, C, a hole or opening, d, like the hole B of fig. 1, being made alongside of and leading from the middle of the curved slit.

Our invention also has advantages over a button-hole formed of two slits, arranged at right angles, as shown in Figure 3, in which f exhibits one and g the other of such slits.

From each of the button-holes exhibited in figs. 2 and 3, a button is very like to become and is easily accidentally detached, for the fly, C, of that shown in fig. 2, will readily yield, so as to allow the head of the shank of the shirt-stud or button to pass out of the button-hole. The button-hole shown in fig. 3 has little or no hold of the button, as in reality it has four flies, h h h h, so flexible as to readily yield, and allow the escape of the button, under very slight force or draught applied thereto.

Our improved button-hole has no fly to yield and admit the escape of the button, and being composed of a close slit, a a, and the hole B leading from its middle, it holds to the button with great tenacity, or, in fact, very much stronger than either of the others, or very much better than will a single wide slit, such as constitutes ordinary button-holes of paper collars.

We do not claim a button-hole composed of a single wide slit, nor of a curved narrow slit, and a hole leading out of its middle and in one side thereof; nor do we claim a button-hole formed of two wide slits, arranged to cross one another at right angles.

What we do claim as our improvement or invention is—

The button-hole, as composed of a close straight slit, a a, and a hole, B, arranged together, substantially as represented in fig. 1 of the above-mentioned drawings.

W. C. REEVES,
LOUIS L. SOLOMON.
